UNITED STATES PATENT OFFICE

EDWARD VAN ANTWERP, OF WHITE BEAR LAKE, MINNESOTA

TARGET THROWING DEVICE

Application filed July 1, 1929. Serial No. 375,135.

This invention relates to improvements in the devices used for the purpose of throwing inanimate targets such as are commonly known as clay pigeons. Its principal advantages are rapidity, safety, and convenience attained in the manner following:

In referring to the drawings that accompany these specifications it is to be noted:

That Fig. 1 shows a side elevation of the device.

That Fig. 2 shows the lower side of tilting table.

That Fig. 3 shows the upper side of tilting table.

Referring to Fig. 1 it is to be noted that No. 1 of this figure represents the base to enable the device to be solidly mounted to foundation or timbers. A perpendicular upright shaft is a part of this base and sliding down over this is upright standard marked No. 2. This standard revolves on shaft and is adjustable to varying positions, being held in the position desired by lever No. 3.

At upper end of standard is an adjustable joint marked No. 4 and mounted in this joint is the tilting table No. 5. This table can be tilted to varying positions and is held at the place desired by lever clamp at joint No. 4. The purpose of this tilting arrangement enables the operator to throw the targets at any desired height.

In this same way lever No. 5 enables him to throw them at any desired right or left angle. On this table No. 5 is mounted the mechanism for discharging or throwing the targets. No. 6 represents electromagnets. No. 7 represents an armature attracted by the magnets. No. 8 represents a small crank to which a connecting rod from armature is attached.

To show this mechanism more in detail reference is had to Fig. 2 and Fig. 3. Fig. 2 represents the under side of table 5. On this are mounted magnets No. 6, movable armature No. 7 and crank No. 8. On this crank opposite the connection of rod from armature a spring is attached to a second crank or lug. This spring, preferably adjustable in tension, is represented by No. 9.

The shaft of crank No. 8 passes through table No. 5 to its upper side.

Fig. 3 shows this upper side of table and the connection of this crank No. 8 to the discharge arm marked No. 10.

No. 11 represents a guide arm adjustable at pivot joint No. 12.

No. 13 represents lugs, preferably of rubber. These lugs may be made so that they are adjustable as to position and thus regulate the length of stroke of discharge arm.

No. 14 represents target in position ready to be thrown.

Wires lead from the electromagnets to the source of electrical supply and a switch marked No. 15 enables the operator to open or close the circuit. This switch should preferably be located back of the shooter's position. A switch form of rheostat is highly desirable to control the strength of the current passing to magnets.

It is to be noted that this method of throwing targets by magnetic attraction is not confined to the ordinary type of electromagnets but instead a solenoid with an armature moving in its magnetic field may be used with like result.

The device is operated in the following manner:—Discharge arm No. 10 is held in its rearward position by spring No. 9. In this position one or more targets are placed on the table near the intersection of arm No. 10 and guide No. 11. When switch No. 15 is closed an electric current passing through magnets attracts armature No. 7 and this being connected to crank No. 8 which in turn is connected to and in reality a part of discharge arm No. 10, causes the said discharge arm No. 10 to throw target outward, its flight being partially governed by the position of guide No. 11. Discharge arm No. 10 automatically returns to the loading position, when no current is flowing. This function being performed by the adjustable spring No. 9.

One of the advantages of a target-throwing device of this kind is the rapidity of operation. The discharge arm returns to loading position after each discharge and no manual labor is required in setting it.

Another advantage is the lessened breakage of targets. Since the armature is at its most remote position from the magnets at the time the switch closes the circuit, the discharge arm and the target start comparatively slowly and rapidly accelerate their speed as armature approaches magnets. This process is just the reverse from the devices formerly used for throwing targets by means of a spring under tension with its tendency to crack and break targets while still in the trap.

It is to be noted that modifications may be made in the shape, position, or arrangement of the parts of this device without departing from the spirit of the invention or sacrificing any of its advantages.

Having thus described my invention I claim the following and desire to protect the same by Letters Patent of the United States.

1. In a target throwing trap, in combination, a base and standard, supporting a table on which are mounted electromagnets, that, when energized by an electric current, operate an armature, a crank, a connecting rod, and a discharge arm; together with a guide to govern the direction of the target, and in addition a flexible element that operates to return the discharge arm to its loading position, substantially as described.

2. In a target throwing trap, energized electromagnetic means operating a discharge arm, said arm returnable to loading position by a flexible element substantially as described.

3. In a target throwing trap, electromagnetic means controlled by a switch and operating a discharge arm through the medium of an armature and connecting means substantially as described.

4. In a target throwing trap, a combination of an armature driven by magnetic attraction, and operating a discharge arm, and a flexible element for returning discharge arm to loading position substantially as described.

In testimony whereof I have affixed my signature this 25th day of April, 1929.

EDWARD VAN ANTWERP.
